L. L. SUMMERS

GAS APPARATUS

Filed May 2, 1921

UNITED STATES PATENT OFFICE.

LELAND L. SUMMERS, OF NEW YORK, N. Y.

GAS APPARATUS.

Application filed May 2, 1921. Serial No. 465,962.

To all whom it may concern:

Be it known that I, LELAND L. SUMMERS, a citizen of the United States, residing at New York, in the county of New York and State of New York, have invented certain new and useful Improvements in Gas Apparatus, of which the following is a specification.

This invention relates to a new and improved method and apparatus for the production of gas, and more particularly to a method and means particularly adapted for the combination into a single continuous operation of the formation of coke and the production of gas therefrom by the water gas process.

The invention comprises the distillation of coal in a coke retort and the immediately subsequent utilization of the coke in a water gas generator. As is well known in the art of water gas generation, a period of air blast in the generator is succeeded by a period during which steam is directed upon the incandescent coke. The gas is formed during the period when the steam is admitted, the air blast simply serving to bring the coke to the proper condition of temperature for the production of the water gas.

It has heretofore been customary in the art to discharge to the atmosphere the products of combustion resulting from the burning of the coke during the air blast. In the present invention this heat resulting from the air blast is utilized for the purpose of heating a coke retort associated with the gas generator. This waste product thus serves a useful purpose in producing the necessary coke.

My invention further contemplates the particular method of operation of the water gas generator so that the period of air blast is adjusted and regulated in such manner as to form a so-called producer gas rather than to cause complete combustion—that is, the amount of air admitted during the blast being insufficient for complete combustion results in a large percentage of carbon monoxide. The products carried off from the generator during the period of air blast therefore possess a heat value made up of the sensible heat of the gas and the chemical energy represented by the carbon monoxide. When these products are introduced into the heating flues of the coke retort, air is admitted, preferably heated from a regenera-

tor, and the carbon monoxide in the gas is burned to carbon dioxide. I therefore utilize in heating the coke retort both the sensible heat and the chemical energy in the gaseous and vaporous products from the water gas generator, together with the hot air from the regenerator. Preferably the coke retorts are arranged in a series of small retorts and I preferably provide also a plurality of water gas generators. In such installations one or more of the water gas generators is constantly upon the air blast, thus producing heat energy for the coking flues. One or more of the gas generators is also constantly generating gas, that is, decomposing the steam into its components, hydrogen and oxygen; the oxygen in turn combining with the carbon of the coke so that the gas generated is the well-known water gas consisting primarily of hydrogen and carbon monoxide, together with a small amount of methane and other hydrocarbons. A retort gas results from the formation of the coke in the coking chambers, and this gas has a relatively high heating value of from 550 to 650 British thermal units per cubic foot. The heat value of the water gas produced represents a thermal energy of about 330 B. t. u. Thus by mixing three parts of water gas to one part of the coke oven gas there is produced four parts of a gas having a heating value in excess of 400 B. t. u. per cubic foot. The exact ratio of mixture necessary will of course depend somewhat upon the quality of the coal used in the coke retort and the resulting coke produced.

It is an object of the present invention to provide an apparatus and a method of operation in which raw coal is coked and the coke produced is discharged directly into water gas generators whereby the high temperature of coke as discharged from the oven is utilized in a water gas generator, thus making it unnecessary in the generator to heat a cold coke bed.

A further object of the invention consists in the utilization of the products and heat of combustion resulting from the air blast in the water gas generator for the purpose of providing the heat necessary to make the coke.

An additional object consists in the utilization of all of the water gas generated by the admission of steam upon the incandescent coke to combine with all of the gas gen-

erated from the distillation of the coal in the coke retort. Thus my invention makes it possible to convert slack coal or high grade coal into a mixed gas of high thermal efficiency. Since all of the coal is fed directly to the coke retort and all of the energy in the coal is utilized with the exception of radiation and similar accidental losses, the resulting efficiency of my process and apparatus is very high.

A very important improvement arising from this invention lies in the fact that the waste products are discharged to the atmosphere only after all such products have been utilized to the fullest extent possible. A further important feature lies in the fact that the continuous process of coking which is used permits an intermittent discharge of coke at such rate that the water gas generator can utilize the coke as discharged. In this method of coking a retort full of coke is not discharged at one time and allowed to cool off, but small quantities of coke are discharged from the oven at high temperature and at a rate adequate for the requirements for the efficient operation of the water gas generator. By the utilization in one installation of a plurality of the generators and of the coke retort, it is possible to so regulate the several generators that heat is constantly being supplied to the coke retort and that the generators are constantly discharging water gas at a rate sufficient for mixture with the gases resulting from the coke retort distillation.

I have illustrated a preferred embodiment of my invention in the accompanying drawings, in which—

Figure 1 is an elevation partly in section showing my apparatus; and

Figure 2 is a transverse section of the apparatus taken on line 2—2 of Figure 1.

The left-hand portion of Figure 1 showing the coke retort is taken substantially on line A—A of Figure 2, while that portion shown in the right-hand part of Figure 1 is taken substantially on the line B—B of Figure 2.

The coking retort shown in the accompanying drawings is substantially that shown in my copending application Serial No. 402,944 filed August 12, 1920 since issued as Patent Number 1,422,634. This retort comprises the coal-receiving hopper 5 and the horizontal retort chamber 6. The floor of this chamber 6 comprises the longitudinally movable floor and fin 7 which is operated by shaft 8 and a piston contained in cylinder 9. The floor 7 is provided with a fin 7', this fin serving to cause greater adhesion of the coke mass to the floor, thus increasing the compression given the coke, as more fully described in my copending application referred to.

The coke retort is provided with the discharge chute 22 having a pair of sealed doors 23. These doors open above a chute 24 which directs the coke to a revolving screen 25. The finer coke may pass through the screen to the hopper 26 and conveyor 27. From the screen the coke passes to the feed hopper 28 of the water gas generator 29, this hopper being closed by the bell valve 30. The generator 29 is provided with the inlet head 31 connected to the pipe 32. A steam pipe 33 is connected to this pipe 32, as shown in the drawing. The bottom of the generator is provided with a sloping ash discharge pit 34 so that the bottom of the generator may be water sealed.

The products formed in the generator are carried off by the pipe 35 through the dust catcher 36 and thus to the pipe 37. This pipe 37 is provided with a cross-head 38 to one side of which is connected a valve 39 and from the upper flange of which an elbow 40 leads to the valve 41. The other branch of the cross member 38 may be blanked off at 42 or connected as will be described hereafter. The valve 39 leads to a cross main 43 from which lead a plurality of distribution pipes 44 extending over the coke retorts. These pipes 44 are provided with a plurality of distribution nozzles 45 which are led downwardly through the regenerative chambers 46 to the coke retort heating flues 47. The regenerative flue 46 is provided with the flue 48 which leads from the flue 47 and with the discharge or air intake opening 49.

The valve 41 is connected to a pipe 50 which leads to the gas collecting main 51 through the regulating valve 52. There is also provided the pipe 53 which leads from the end of the coke retort 6 to the pipe 50 adjacent the valve 52, being itself controlled by the valve 54. The pipe 37 may be connected to the header 55 by the tee 56, which header is provided with a plurality of pipes 57 leading into the ends of the coke retort heating flues.

In the operation of my invention, the hopper 5 is filled with coal and the water gas generator 29 is filled with coke. The coal from the hopper 5 is passed down upon the ram or floor by gravity and is carried forward upon that ram by the reciprocating motion given the ram or floor by the shaft 8 and cylinder 9. That is, as the ram or floor is pulled outwardly there is a tendency for the coal or coke upon the ram or floor to be compressed against the bulkhead and the solid mass of coal extending upon the outer end of the ram or floor from the hopper 5. A certain amount of the finished product, however, upon the inner end of the ram or floor falls down through the chute 22. As the ram is moved inwardly again, the coal is moved away from the chute 5.

and additional coal falls down. This operation is continuous at proper intervals to secure adequate coking.

As pointed out in my Patent 1,422,634 previously referred to, in coking retorts being of relatively great height and small width, the fin 7 aids greatly in this compression of the coke, due to the increase in effective area it gives the ram.

10 The coke passing through the sealed doors 23 and through the screen 25 is fed into the generator feed hopper 28 and thence as needed into the generator 29. Air is blown through the pipe 32 and head 31, being preferably so regulated as to cause only partial combustion of the coke with the formation of carbon monoxide. This carbon monoxide passes up through the dust catcher 36 and pipe 37 and out through the header 43 and 15 pipes 44, the valve 41 being closed. From pipes 44 the gas is distributed to the nozzles 45 which lead to the combustion flue 47. It is to be understood that the regenerative chamber 46 is duplicated above the coking 20 retort, so that air will pass down through the port 49' and through the regenerative flue 46' and thus into the chamber 47. This air joins with the carbon monoxide and burns and the products of combustion are 25 carried out through the port 48 and through the regenerative flue 46 to the outlet 49. These chambers 46 and 46' are intermittently reversed according to a well-known regenerative principle, so that the air brought in for 30 combustion is continuously heated. When the air blast has been on for a sufficient length of time in the gas generator, the air is cut off and steam introduced from the pipe 33 through the head 31. At this time the valve 39 is closed and valve 41 opened, the water 35 gas generated thus being carried off through the pipe 50 and valve 52 to the gas main 51.

It is to be understood that since a plurality of retorts and generators are combined in a 40 single installation the header 43 is constantly receiving the carbon monoxide and other air blast products from one or more generators, so that there is no interruption of the combustion in the flues 47 while gas is being 45 generated in any particular generator. Similarly the gas main 51 is constantly being supplied with water gas and this action goes on also without interruption.

50 It will be apparent from the drawing and description that the interposition of the screen 25 between the coke chute and the gas generator enables the coke to be screened and if desired a certain proportion of the coke

may be taken off by the conveyor 27. Also if desired the head 42 of the cross member 38 60 may be connected to any desired apparatus to utilize any excess heat from the waste products of the air blow to the generator, as for example; this heat may be carried to steam generators for supplying the steam or to any other apparatus.

It is possible to utilize my system in such manner that the heat exchanges are constant, or it may be adjusted to produce an excess 70 of coke, or otherwise adjusted to produce an excess of gas. The gas generator is of continuous type due to the continuous introduction of coke into the hopper 28, from which it is fed as needed to the generator 75 through the bell valve 30; and the ashes may be continuously removed as necessary through the water seal 34. The shifting of the air blast and steam blast and of the discharge from the generator to the coke retorts and gas main may be accomplished by a system of interlocking valves, as is standard 80 in the art and need not be shown or further described since it in itself forms no part of the present invention.

The particular embodiment shown is 85 simply one apparatus capable of accomplishing my preferred method of gas generation and it is to be understood that it is illustrative only. The principle may be utilized 90 in the operation of other devices as covered by the following claims.

I claim:

1. Apparatus for producing gas from coal comprising a coking apparatus of a type 95 intermittently discharging a part of its contents, a gas generator associated therewith, a feed hopper upon the generator adapted to receive the coke as discharged from the oven, and screening means interposed between the oven and generator and adapted to eliminate certain portions of the coke before it reaches the generator.

2. Apparatus for producing gas from coal comprising a coking apparatus of a type 100 intermittently discharging a part of its contents, a gas generator associated therewith, a feed hopper upon the generator adapted to receive the coke as discharged from the oven, a rotary screen interposed between the oven 105 and generator adapted to eliminate coke below a predetermined size, and a conveyor 110 associated with the screen and adapted to remove the eliminated coke.

Signed at New York, New York, this 22nd day of April, 1921.

LELAND L. SUMMERS.
